UNITED STATES PATENT OFFICE.

FREDERIC T. MURLESS, JR., OF HARTFORD, CONNECTICUT.

LOCKING MEANS FOR ORTHODONTIA APPLIANCES.

1,347,285.

Specification of Letters Patent.

Patented July 20, 1920.

Application filed March 26, 1920. Serial No. 369,022.

To all whom it may concern:

Be it known that I, FREDERIC T. MURLESS, Jr., a citizen of the United States, residing at Hartford, in the county of Hartford and State of Connecticut, have invented a new and useful Improvement in Locking Means for Orthodontia Appliances, of which the following is a specification.

10 This invention relates to the means provided for securing the lingual and buccal arches to the anchor bands employed in orthodontia, or the mechanical treatment for correcting the irregularities and faulty 15 positions of teeth. Such appliances are of necessity very small, they are used in constricted spaces, and are more or less difficult to reach and manipulate.

The object of this invention is to construct a light, cheap and unobtrusive means for locking or unlocking the ends of lingual and buccal correcting arches to anchor bands placed around teeth on the upper or the lower jaw, which will securely hold 25 the parts together and can be easily and quickly manipulated in restricted localities without disturbing the gums.

This object is attained by forming pockets on the sides of the anchor bands, providing the ends of the arch wires with radially projecting studs shaped to fit the pockets and attaching to the arch wires yielding fingers that are designed to snap into notches in the walls of the pockets when 35 the studs are thrust into the pockets and prevent the withdrawal of the studs from the pockets until the ends of the fingers are sprung out of the notches, which cannot take place accidentally.

40 Figure 1 of the accompanying drawings shows on greatly enlarged scale a plan of an anchor band with the end of an arch wire secured thereto according to this invention. Fig. 2 is a side view of the band and arch connected. Fig. 3 is a side view with the band and arch disconnected. Fig. 4 shows a plan of the band. Fig. 5 shows a form of lock of slightly different shape.

The anchor band 1 is made the desired 50 shape and size of the usual metal, commonly gold and platinum alloy. On the inner or outer side of the band, as required by the use to which it is to be put, and extending part of the length of the band is 55 a pocket which is conveniently formed by soldering a tube 2 of the desired cross sec-

tion, preferably semi-circular, to the wall of the band. The edge wall of the pocket is cut away to form a notch 3 that opens toward the front.

60 The correcting arch 4, lingual if for use on the inside of the teeth and buccal if for use on the outside of the teeth, is formed of the necessary length of wire of the usual alloy. A stud 5 of such cross section that it will fit closely within the pocket on the side of the anchor band is secured to the arch wire near its end. It is preferred to form a notch 6 in the front edge of this stud in such a locality that the notches will 65 align when the stud is in the pocket. A resilient locking finger 7 is secured to the arch wire at a convenient distance from the stud and is curved around in such shape that its end 8 will project toward and 70 slightly into the notch in the edge of the stud. As shown in Fig. 3, this locking finger may extend downward from the arch wire and then curve upward and backward toward the stud, or it may extend 75 outward from the arch wire and curve toward the stud, as does the finger 9 shown in Fig. 5. It is convenient to have the upper corner of the front edge of the wall of the pocket beveled off as at 10, and 80 to have the end of the finger cut off at an angle as at 11 so that when the parts are to be put together and the stud is thrust 85 into the pocket the inclined surfaces on the edge of the pocket and the end of the finger will coact to push the finger outward until the connection is completed, when the end of the finger will spring into 90 the notches where it will remain holding the parts together securely. By the employment 95 of a suitable instrument the end of the finger may be readily pulled out of the notches and the stud released when it is desired to disconnect the end of the arch wire from the anchor band.

100 This construction is very simple, cheap and easily manipulated. The locking finger is slight, and in the form shown very yielding, so that it can be easily sprung out and yet when it is sprung into the notches it 105 securely holds the stud from being withdrawn from the pocket.

The invention claimed is:—

1. Locking means for connecting an orthodontia anchor and arch which comprises 110 a pocket with a hole through its side, formed on the wall of the anchor, a notched

stud extending at an angle from the arch into said pocket, and a yielding finger projecting from the arch and having its ends extending through the hole in the pocket 5 into the notch in the stud.

2. Locking means for connecting an orthodontia anchor band and arch wire which comprises a vertical pocket having a hole through its side wall formed on the side 10 of the band, a stud projecting radially from the arch wire and shaped to fit the pocket, and a curved finger projecting from the arch wire and having its end adapted to spring into the hole in the wall of the pocket 15 when the stud occupies the pocket.

3. Locking means for connecting an orthodontia anchor band and arch wire which comprises a tube that is semi-circular in cross section and has a hole through one 20 side secured to the band, a stud that is semi-

circular in cross section projecting from the arch wire into said tube, and a spring finger projecting from the arch wire into the opening through the side wall of the tube.

4. Locking means for fastening the end 25 of an orthodontia arch wire to an anchor band, which comprises a pocket formed on the side of the band, said pocket having a notch in its front edge and its end edge beveled, a stud projecting radially from the arch wire and shaped to fit the pocket, and a spring finger projecting from the arch wire and curving toward the stud, said finger having its end cut on an angle and 30 adapted to spring into the notch in the pocket when the stud is thrust into the pocket. 35

FREDERIC T. MURLLESS, JR.
